BLADE BLOCKS IN HYDRAULIC COUPLINGS

Maurice Foster, deceased, late of Rockford, Ill.,
by Richard T. Rehwald, administrator, Rock-
ford, Ill., assignor to Twin Disc Clutch Com-
pany, Racine, Wis., a corporation of Wisconsin

Application November 23, 1946, Serial No. 711,965

4 Claims. (Cl. 103—115)

1

The invention relates to hydraulic couplings and more particularly to an arrangement thereof which enables a given size coupling to be used at several horsepower ratings.

Hydraulic couplings are employed in such a variety of installations with corresponding requirements as to horsepower that a manufacturer is faced with the task of building a large number of sizes if it is desired to provide a complete line of units. This situation is uneconomical from a manufacturing standpoint.

It is therefore the principal object of the invention to provide a hydraulic coupling which is constructed and arranged so that the capacity of any given unit may be reduced to meet any selected requirement as to horsepower less than its normal rating for size whereby a material reduction may be effected in the number of sizes offered by a manufacturer.

A further object is to provide a coupling of the character indicated in which capacity variation is effected by blocking as many passages in the impeller or runner as are necessary to secure the desired reduction.

A further object is to devise a blade block formed as a simple stamping, selected numbers of which are positioned in balanced relation in the outer ends of the impeller or runner passages to accomplish the foregoing results.

These and further objects of the invention will be set forth in the following specification, reference being had to the accompanying drawing, and the novel means by which said objects are effectuated will be definitely pointed out in the claims.

In the drawing:

Fig. 1 is a sectional elevation showing a portion of a twin circuit, hydraulic coupling modified in accordance with the invention.

Fig. 2 is a perspective view of a blade block.

Fig. 3 is a view of the channel side of the block.

Fig. 4 is a view looking in the direction of the arrow 4 in Fig. 3.

Referring to Fig. 1 of the drawing, the numeral 10 designates an engine flywheel which is to be generically considered as any source of power and to which is bolted an internally toothed, driving ring 11 that meshes with an externally toothed, driven disk 12. The inner rim of an impeller 13 is clamped by means of studs 14 between the disk 12 and a ring 15 located inwardly of the impeller and the outer rim is shaped to receive one end of a spacer ring 16 whose opposite end is received within the correspondingly shaped outer rim of an impeller 17 that is positioned in facing rela-

2

tion to the impeller 13. A plurality of circumferentially spaced bolts 18 extending through the spacer ring 16 secure the impellers together and leakage of the working liquid, usually an appropriate oil, in this locality is prevented by packing 19—19 between the ends of the ring 16 and the adjacent portions of the impeller rims. The inner rim of the impeller 17 is claimed between a ring 20 located inwardly of the impeller and an outer ring 21 by means of a plurality of studs 22. The impeller 13 is provided with a plurality of radial blades 23 and a core ring 24, thus defining a plurality of radial liquid passages. Similarly positioned and secured blades 25 are arranged around the impeller 17 in conjunction with a core ring 26 to form like liquid passages.

A runner 27 having a plurality of radial blades 28 defining therewith and a core ring 29 a plurality of radial, liquid passages is located in facing and cooperating relation to the impeller 13 and a similar runner 30 having blades 31 and a core ring 32 defining like radial, liquid passages is positioned in facing and cooperating relation to the impeller 17, thus forming a pair of liquid working circuits. From the foregoing, it will be understood that the runners 27 and 30 constitute the inner shells of their respective working circuits, while the outer shells are formed by the impellers 13 and 17. However, power flow through the coupling may be reversed without affecting its operability and, in this event, the runners 27 and 30 act as impellers and the impellers 13 and 17 serve as runners.

The respective core rings are held in position by a pair of fins 33 on each associated blade which extend through slots of appropriate shape in the rings and are suitably expanded or upset to provide a rigid connection. This type of connection is intended to indicate a representative mode of securement only.

The inner portions of the runners 27 and 30 are secured to a hub 34 that is keyed to a driven-shaft 35 journaled in bearings 36 and 37 whose outer races are carried by the rings 15 and 20, respectively. The disk 12 closes the forward end of the coupling around the end of the shaft 35, while the rear end is sealed by a packing ring 38 that encircles the shaft 35 and is carried by the outer ring 21.

So far as described, the coupling is of characteristic construction. The invention resides in the use of a blade block, any number of which may be employed to close a corresponding number of the radial passages in the impeller or runner to accordingly vary the capacity of the coupling,

For convenience, these blocks are shown as applied to the runners 21 and 30.

Referring to Figs. 2, 3 and 4, the blade block, designated by the numeral 39, is first formed as an inverted, U-shaped stamping comprising a pair of spaced wings 40—40 that are connected by a web 41. The wings 40 are then bent laterally from the web 41 to form the channel block 39 shown in Fig. 2. Considering the runner 21, for example, the upper edge 42 of each wing 40 is curved to fit the curved outer wall 43 of the runner, while the side edges 44 and 45 are straight and relatively tapered to abut and conform to the radial, runner wall 46 and the core ring 29, respectively. As shown in Fig. 3, the wings 40 taper towards each other from the web 41 for easy fitting with the blades 28 of the runner passage in which the block is inserted.

The number of blocks used will depend upon the reduction in torque capacity desired, and this number having been determined, they are spaced around the runner so that the latter's balance is not disturbed. This operation is normally effected at the place of manufacture and before the core ring 29 is connected to the blades 28. Each block is telescoped within the selected radial passage of the runner with the wings 40 sliding along the blades 28 which partially define the particular passage until the block assumes the position shown in Fig. 1 with the web 41 completely closing the entrance to the runner passage. The core ring 29 is then connected to the blades by the fins 33 to thereby hold the block in the position shown. The same procedure is followed for the runner 30.

Without the blocks 39, the coupling is characterized by its normal slip and its full rated torque capacity for the particular size. However, the addition of the blocks eliminates a like number of runner passages from the working cycle of the coupling and so increases the latter's slip with a corresponding reduction in the torque capacity. For any size coupling, there is obviously considerable flexibility in the amount of capacity reduction that may be effected with this construction. Whatever the number of blocks may be, the operating characteristics of the coupling are stable, and it has been ascertained that the torque capacity drops almost directly with the number of passages blocked and that the drag torque, or torque with the runner stalled, decreases in about the same proportion. Hence, it is possible to determine with practical exactness the amount of capacity reduction any particular number of blocks will provide. Further, the improvement possesses the outstanding advantages of cheapness, simplicity, ease of application, and of not requiring any major design changes in the coupling proper.

The blocks may be positioned in the runner or impeller, and if in the latter, the block may require minor reshaping for fitting in the outlets

of the impeller passages. The general shape of the impeller block, however, would be as shown in Fig. 2. The blocks may also be used in either element of a single circuit coupling.

What is claimed is:

1. An hydraulic coupling member including an annular shell, an annular core ring and radial blades cooperably related to define radial passages, and fixed blade blocks inserted in selected and less than all of the passages, each block including a web closing the outer end of the associated passage and wings telescopically related to the adjacent blades.

15 2. An hydraulic coupling member including an annular shell, an annular core ring and radial blades cooperably related to define radial passages, and fixed blade blocks inserted in selected and less than all of the passages, each block including a web closing the outer end of the associated passage and wings telescopically related to the adjacent blades, the side edges of the wings being relatively tapered for interlocking engagement with the shell and core ring.

20 3. An hydraulic coupling member including an annular shell, an annular core ring and radial blades cooperably related to define radial passages, and means for blocking a passage comprising a pair of wings inserted in said passage and abutting the opposed surfaces of the associated blades, respectively, and a web bridged between the wings and sized to close said passage.

25 4. An hydraulic coupling member including an annular shell, an annular core ring and radial blades cooperably related to define radial passages, and means for blocking a passage comprising a pair of wings inserted in said passage and abutting the opposed surfaces of the associated blades, respectively, and a flat web bridged between one end of each wing and sized to close said passage, the opposite ends of the wings being relatively tapered for interlock with the ring and shell.
